DESIGN FOR A TRANSLUCENT DARNER

Leenore von Meissner, New York, N. Y.

Application August 21, 1940, Serial No. 94,537

Term of patent 7 years

To all whom it may concern:

Be it known that I, Leenore von Meissner, a subject of the King of Sweden, residing at New York, New York, whose post-office address is 68 West 58th Street, New York, New York, have invented a new, original, and ornamental Design for a Translucent Darner, of which the following is a specification, reference being had to the accompanying drawing, forming part thereof.

Figure 1 is an elevational view of a translucent darner in a closed position; and

Figure 2 is an elevational view of the same in open position, showing my new design.

I claim:

The ornamental design for a translucent darner, as shown.

LEONORE VON MEISSNER.
